UNITED STATES PATENT OFFICE.

EDWIN BURHORN, OF HOBOKEN, NEW JERSEY.

COOLING-TOWER.

972,163.

Specification of Letters Patent. Patented Oct. 18, 1910.

Application filed April 30, 1910. Serial No. 558,596.

To all whom it may concern:

Be it known that I, EDWIN BURHORN, a citizen of the United States, residing in the city of Hoboken, county of Hudson, and 5 State of New Jersey, have invented certain new and useful Improvements in Cooling-Towers, of which the following is a specification.

My invention relates to cooling towers or 10 that class of device employed for modifying the temperature of water or other liquid which is to be sprayed or otherwise passed through the apparatus in contact with cooling air or other medium.

15 My present invention contemplates improvements in certain of the features of such cooling towers, which together with the objects accomplished, will appear in the following description.

20 I will first describe one form of apparatus embodying my improvements and then point out the novel features in the claims.

In the drawing accompanying and forming a part of this specification, Figure 1 is 25 a side elevation of a cooling apparatus embodying my improvements with certain parts omitted to more clearly show the interior arrangement, and Fig. 2 is an enlarged detail showing the form and relative position 30 of two successive louvers. Fig. 3 is an elevation of a single one of the louvers detached, showing its relative length and width.

Similar letters of reference designate cor- 35 responding parts in the several figures of the drawings.

In an apparatus of this kind, there is a 40 space through which water is to be passed, for example by showering, and it will be understood that the water is to be under the constant influence of a medium such as air for lowering or modifying the temperature of the water.

The details of any particular mechanism 45 for forcing air into the apparatus are not a part of the present invention, and are therefore not illustrated, and indeed any special apparatus for this purpose may under proper conditions be dispensed with since 50 the in-flow of atmospheric air may be adequate.

There is a general framework designated by A, whose details will not be referred to further than to explain that the same consists of upwardly extending and also trans- 55 verse members properly interconnected to

constitute a rigid tower, at the top of which water may be showered and from the bottom of which water may be drawn by a suitable outlet. 60

B represents a pan located at the bottom and of sufficient size to catch all the water which may drop or splash in the apparatus.

C is an outlet from the pan B. The cooled water from outlet C may be passed through 65 the condenser of a steam-engine or otherwise employed in accordance with the purposes of the cooling tower.

D represents a showering device located at the top and which is connected in any 70 suitable way as by a pipe E with the source of hot water or other medium to be cooled or modified in temperature.

The water from the showering device D passes successively through any desired number of decks or pans F, G, H, which are preferably in the form of perforated and flanged pans which assist in the proper distribution of the descending streams of water. 75

J represents a series of louvers on the 80 right-hand side of the apparatus and there will preferably be a similar series K on the opposite side, and when the tower is four-sided, two further series, namely on the side farthest from the observer of Fig. 1, and on 85 the side nearest the observer, which latter are omitted from the drawing for the sake of clearness. The louvers will be observed to be inclined inwardly, by which I mean that any stray water falling upon the upper 90 surface of a given louver will tend to flow inwardly rather than outwardly. The different louvers in each series are superposed, that is placed one above the other, and the arrangement will be seen to be such as to 95 practically constitute a wall against the accidental loss of water which is liable to be thrown or splash outwardly; whereas on the contrary passage for cooling currents of air is permitted. Indeed the entering air is 100 thrown in an inclined direction which cuts the descending streams of water diagonally so as to increase efficiency.

Each of the louvers marked N in Fig. 2 is seen to consist generally of a flat strip or 105 sheet of metal, wood or other suitable material, the same being comparatively thin so as to minimize obstruction, weight and expense. A channel at O is shown along the upper side or edge of each louver, this conveniently 110 being formed by a bending over of the metal, as seen in Fig. 2. In the case of wa-

ter tending to become lost by being thrown outwardly from the spraying devices, the channel O would act as a barrier preventing the out-flow of water, and would even serve to hold loose water until sufficient quantity had accumulated to make heavy drops which would then necessarily run back or inward. In addition to the channel O is shown a groove P running along the lower side or edge of each louver. Into this groove will run all of the water accumulated upon the upper surface of the louver. The advantage of this construction can now be made clear. If the upper surface of the louver were perfectly plain and flat, not only would some of the water be liable to be lost by passing outwardly, but that water which runs inwardly and drops back into the tower might in some cases constitute a substantial descending sheet of water that would materially obstruct the free in-flow of the cooling air between the louvers. This objection would be quite serious, especially in the case of an apparatus to be operated by the natural movements of atmospheric air, which in some cases would be of very light pressure. Instead of acting in this manner, the groove P gathers all the water from the surface of the louver, finally discharging it into the interior of the tower at certain designated or predetermined points at which discharge openings may be formed; and in the present case these discharge points will be at the two ends respectively of the groove P on each louver. The combination of elements above described, therefore, beside the benefits already mentioned serves to gather all the loose water from the louvers into substantially four descending streams, namely at the four corners of the tower.

It will be understood that the air passing inwardly between the louvers at one side will subsequently pass outwardly from the tower between the louvers at the opposite side, and it is therefore important to minimize the obstruction to the air passing outwardly. This is materially assisted by the peculiar construction of louver, as shown in Fig. 2, wherein the bottom edge Q at the extreme lower side, is in the same plane with the upper face of the louver and does not project above the latter. By this means the groove P is located or formed entirely be-

nath the upper surface of the louver for the purposes specified.

The particular manner shown of connecting the louvers to the frame is merely one convenient form of connection, and may be varied as desired, and it will be understood that many variations in the louvers themselves are within the scope of the present improvement; they may, for example, be made adjustable for inclination or otherwise; and any of the features already referred to in my prior applications No. 65 408,379 filed Dec. 28, 1907 and No. 501,488, filed June 11, 1909, may be adopted in connection with the present improvements.

What I claim as new and desire to secure by Letters Patent, is:

1. In a cooling tower, the combination of the framework with means to pass the liquid to be cooled from the upper to the lower portion, and a series of superposed and inwardly inclined louvers each having a channel along its upper edge.

2. In a cooling tower, the combination of the framework with means to pass the liquid to be cooled from the upper to the lower portion, and a series of superposed and inwardly inclined louvers each having a channel along its upper edge; and a groove running along the louver's lower edge.

3. In a cooling tower, the combination of the framework with means to pass the liquid to be cooled from the upper to the lower portion, and a series of superposed and inwardly inclined louvers each having a channel along its upper edge; and a groove running along the louver's lower edge, said groove formed entirely beneath the upper surface of the louver.

4. In a cooling tower, the combination of the framework with means to pass the liquid to be cooled from the upper to the lower portion, and a series of superposed and inwardly inclined louvers, each having a groove running along its lower edge from end to end.

In witness whereof I have hereunto set my hand, this 29th day of April, 1910.

EDWIN BURHORN.

Witnesses:

FRANCES KINREICH,
DONALD CAMPBELL.
